UNITED STATES PATENT OFFICE

129,382

DESIGN FOR A FURNITURE FLOWER STAND OR SIMILAR ARTICLE

Leo Reimer, New York, N. Y.

Application July 1, 1941, Serial No. 101,839

Term of patent 7 years

To all whom it may concern:

Be it known that I, Leo Reimer, a citizen of the United States, residing at 20 Metropolitan Oval, in the city of New York, county of Bronx, State of New York, have invented a new, original, and ornamental Design for a Furniture Flower Stand or Similar Article, of which the following is a specification, reference being had to the accompanying drawing, forming part thereof.

Fig. 1 is a perspective view of a furniture flower stand showing my new design.

Fig. 2 is a front view of the furniture flower stand shown in Figure 1.

I claim:

The ornamental design for a furniture flower stand or similar article, substantially as shown.

LEO REIMER.
